DESIGN FOR A SINK STRAINER

Charles E. Caestecker, Kenilworth, Ill., assignor
to American Molded Products Co., Chicago, Ill.,
a corporation of Illinois

Application July 26, 1944, Serial No. 114,565

Term of patent 14 years

(Cl. D44—29)

To all whom it may concern:

Be it known that I, Charles E. Caestecker, a citizen of the United States and a resident of Kenilworth, in the county of Cook and State of Illinois, have invented a new, original, and ornamental Design for a Sink Strainer, of which the following is a specification, reference being had to the accompanying drawing, forming part thereof.

Figure 1 is a top plan view of the sink strainer embodying my new design.

Figure 2 is a bottom plan view thereof, and
Figure 3 is a side elevational view of Figure 1.

I claim:

The ornamental design for a sink strainer, substantially as shown.

CHARLES E. CAESTECKER.
